Application December 28, 1948, Serial No. 150,402

Term of patent 14 years

(Cl. D54—12)

To all whom it may concern:

Be it known that we, Irving L. Hirsch and Joseph C. Hirsch, both citizens of the United States, residing at Englewood and New York, in the county of Bergen and New York and State of New Jersey and New York, respectively, have invented a new, original, and ornamental Design for a Serving Fork or Similar Article, of which the following is a specification, reference being had to the accompanying drawing, forming a part thereof:

In the drawing:

Fig. 1 is a perspective view of a serving fork or similar article, showing our new design;

Fig. 2 is a side elevational view of the handle only shown in Fig. 1;

Fig. 3 is a top plan view of Fig. 2;

Fig. 4 is an end elevational view looking at the left hand of Fig. 3; and

Fig. 5 is another end elevational view looking at the right hand end of Fig. 3.

The essential features of our design reside in the parts shown in full lines in Fig. 1, the broken lines being omitted from the other figures for convenience of illustration.

We claim:

The ornamental design for a serving fork or similar article, substantially as shown and described.

IRVING L. HIRSCH.
JOSEPH C. HIRSCH.
